UNITED STATES PATENT OFFICE.

BENJAMIN H. MARSHALL, OF CHICAGO, ILLINOIS.

DESIGN FOR A PUZZLE-BOARD.

SPECIFICATION forming part of Design No. 29,906, dated December 27, 1898.

Application filed November 19, 1898. Serial No. 896,942. Term of patent 7 years.

To all whom it may concern:

Be it known that I, BENJAMIN H. MARSHALL, a citizen of the United States of America, residing at Chicago, in the county of Cook and State of Illinois, have invented and produced a new and original Design for Puzzle-Boards, of which the following is a specification, reference being had to the accompanying drawings, forming a part hereof.

Figure 1 is a plan view of a puzzle-board, showing my design; and Fig. 2 is a central transverse section.

My design consists in the outline and surface ornamentation of the puzzle-board. The edge A of the board is elliptical in plan view, with pointed ends. At each end of the board is a miniature representation of a large island B, and extending between these large islands

is a series of miniature representations of small islands C. These small islands are of varying sizes and of irregular outline, presenting tortuous spaces or passages D, and they approximately follow the medial line of the board, leaving large blank spaces E between themselves and the central portions of the edge of the board.

Having thus described my invention, what I claim, and desire to secure by Letters Patent, is—

The design for a puzzle-board herein described and shown.

BENJAMIN H. MARSHALL.
